OR D15,835 EX

DESIGN.

A. LANGENBAHN, O. C. EVANS & C. HIBY.

BAS RELIEF.

No. 15,835.

Patented Feb. 17, 188

UNITED STATES PATENT OFFICE.

ADOLPH LANGENBAHN, OSCAR C. EVANS, AND CHARLES HIBY, OF HAMILTON, ONTARIO, CANADA.

DESIGN FOR A BAS-RELIEF.

SPECIFICATION forming part of Design No. 15,835, dated February 17, 1885.

Application filed December 12, 1884. Term of patent 3½ years.

To all whom it may concern:

Be it known that we, ADOLPH LANGENBAHN, OSCAR CHARLES EVANS, and CHARLES HIBY, citizens of the Dominion of Canada, residing at Hamilton, in the county of Wentworth and Province of Ontario, have invented and produced an original Design for a Bas-Relief, of which the following is a description.

The nature of our invention of the new design is fully represented in the accompanying photographic illustration, to which reference is made.

A represents the shield, of which the top part contains thirteen stars in relief. The lower part of shield is divided into vertical fillets to form the stripes. The shield A forms the background of portrait medallions B and C. A lower wreath encircles both medallions. An eagle surmounts the shield A.

We are aware that the design of the shield 20 is not new, and we do not claim it.

The distinctive character of our design is found in the portrait medallions on the shield as background with foliage or ornaments.

What we claim as our invention is--

The design for a bas-relief, with the shield of the shape shown as background, ornamented with laurel leaves or ornaments, substantially in the manner shown and described. 25

A. LANGENBAHN.
